ABSTRACT OF THE DISCLOSURE

A steam cracking feed mixture containing steam and hydrocarbon is conventionally cracked in the tubes of a steam cracking furnace. The conversion of hydrocarbon to cracked product can be increased by injecting a high temperature gaseous stream such as can be produced by electrical heating, into the mixture in the cracking furnace or into the mixture as it emerges from the cracking furnace, thus subjecting the furnace effluent to short residence time, high temperature cracking conditions. In one method, methane is electrically heated and cracked to a mixture comprising acetylene and hydrogen, which is then injected into the product from the steam cracker, thereby causing additional cracking of the steam cracker feed and quenching of the electrically cracked product to preserve the acetylene content thereof. The electrically heated stream may, however, contain hydrogen, steam, hydrocarbons, e.g. acetylene, or mixtures thereof as the components of greatest concentration.

FIELD OF THE INVENTION

This invention relates to an improved steam cracking process. More specifically, this invention relates to a steam cracking process wherein the conversion of hydrocarbon feed to cracked product is increased by injecting into the steam cracking mixture, while still in the furnace but preferably as it leaves the furnace, an electrically heated gaseous stream at a temperature higher than that of the steam cracking mixture. The electrically heated gaseous stream may comprise, as the component, in greatest concentration, steam, hydrogen, electrically cracked hydrocarbons or mixtures of the foregoing. In a preferred embodiment, methane or other low value hydrocarbon material produced in conventional steam cracking operations is separated from the steam cracking product, electrically heated and cracked in high conversions to acetylene and hydrogen, and the hot acetylene-hydrogen mixture is injected into the steam cracking product to further crack the hydrocarbon feed and quench the electrically cracked product to preserve the acetylene. In this manner, rather low value products can be recycled to extinction and utilized to produce more valuable products.

PRIOR ART

Conventional steam cracking processes are generally well known to the art and have been widely used in the preparation of valuable unsaturated materials, e.g. ethylene, propylene, butadiene, particularly ethylene. Nevertheless, the yield of cracked products such as ethylene and the level of conversion of hydrocarbon feed to the cracking furnace is greatly limited by metallurgy, coking tendency, and heat transfer rates. Thus, steam cracking is effected by passing a mixture of steam and a hydrocarbon feed through metal tubes arranged in a cracking furnace. The tubes are then exposed to convective and radiant heat which is transferred through the tube walls and to the reactants within the tubes, thereby causing the hydrocarbon feed to crack. Of course, the higher the temperature to which the hydrocarbon feed can be exposed

2

the greater the extent of the cracking process, i.e., greater conversion. (Conversion is defined as weight percent of feed converted to C_3 and lighter material.) However, available metallurgical techniques have not yet devised tube metal materials that can continuously stand up to metal temperatures in excess of about 2000° F. Further, inhibiting the cracking of the feed is the tendency of the feed, when cracked, to deposit coke on the interior of the tube walls. Now, since coke is a thermal insulator, i.e. has poor heat transfer qualities, less heat is transmitted to the feed, thereby lowering the temperature level and reducing the amount of cracking that can be effected. Obviously, raising furnace temperatures is not satisfactory in view of the maximum operating limit of the tube metal already mentioned. Because of the foregoing factors, then, conversions in conventional steam cracking processes are limited to about 30-50% on feedstocks in the gas oil boiling range, and to 50-70% on naphtha feeds; ethylene yields, depending on feedstock, are limited to about 20-30%. However, by utilizing the process of this invention, which allows a simple method for boosting the temperature of the steam cracking reaction mixture, markedly increased overall conversions and increased ethylene yields can be obtained. For example, conversions can be increased by 50% or more to about 60+ C_3 - weight percent on feed, preferably 65+%, even with heavy feedstocks, and C_2 -unsaturate, e.g. ethylene, acetylene, yields can similarly be increased by a factor of 1.2-2 up to about 35-45% or even higher.

SUMMARY OF THE INVENTION

In accordance with the invention, therefore, an improved cracking process is provided which comprises passing steam in admixture with a suitable hydrocarbon feed through metal tubes arranged in a cracking furnace, exposing the tubes to sufficient convective and radiant heat, such that the heat transferred to the reaction mixture in the tubes is sufficient to crack the hydrocarbon passing therethrough, and injecting into the cracked product, either while it is still within the radiant section of the cracking furnace or after emerging from the cracking furnace, a gaseous electrically heated stream having a component preferably of greatest concentration selected from the group consisting of inert gases, hydrogen, steam, cracked hydrocarbons, e.g. acetylene, and mixtures thereof, thereby subjecting the cracked product to short residence time, high temperature cracking conditions, the electrically heated stream being at a higher temperature than the steam cracked product mixture and causing additional cracking of the hydrocarbon feed to the steam cracking process. In a preferred embodiment of this invention, any excess hydrocarbon product from the steam cracking operation, preferably methane, is separated downstream from the steam cracker, passed through an electric arc which cracks the methane to a gaseous stream rich in hydrogen and acetylene, the stream being quenched by injecting it into the steam cracker effluent, thereby providing sufficient additional heat to cause further cracking of unconverted hydrocarbon feed.

DRAWING DESCRIPTION

A better understanding of the invention described herein will be had by reference to the drawing attached hereto. The attached drawing shows in schematic outline, a typical process for increasing the conversion of steam cracking processes. Turning now to the drawing, hydrocarbon feed in line 10 is admixed in suitable proportions with steam in line 11 and the feed mixture is introduced into tubes (not shown) arranged generally in a parallel fashion, in steam cracking furnace 12. The furnace can contain a multiplicity of tubes which are heated in any suitable fashion, e.g. combustion of gases, etc. Normally,

steam cracking furnaces contain two sections, i.e. a convection section wherein the feed is vaporized, if not already in the vapor state, and heated to about 1000-1100° F. but below that temperature at which cracking starts, and, a radiant section where the vaporized feed is quickly heated to temperatures ranging from 1200° to about 1800° F. and cracked. The product of the cracking furnace comprising steam, cracked product, and unconverted feed, in line 13 is then mixed as soon as possible after leaving the furnace, e.g., before any significant temperature loss, with a gaseous electrically heated stream which is at a temperature of about 2500°-4000° F. in line 14. The additional heat supplied by the stream in line 14 is sufficient to cause additional cracking of the unconverted hydrocarbon feed in post-reactor 16, after which the total product in line 17 is introduced into heat exchanger or quench line 18 wherein a quench oil from line 19 can be added to inhibit any further reaction. The quenched product at about 300-700° F. in line 20 is then transferred to a fractionator 21 wherein the various products are separated, for example, hydrogen in line 27, acetylene in line 23, ethylene and ethane in line 24, and C₃+ in line 25. Methane, however, in this embodiment, is separated in line 22 and sent to pre-heater 26 wherein the temperature is raised to about 500 to 1500° F. and thence to electric arc heater 27 wherein the methane is cracked, in large part, to hydrogen and acetylene in line 14. Some of the hydrogen in line 27 may be recycled (not shown) to the arc to suppress coke formation when cracking a hydrocarbon.

PREFERRED EMBODIMENTS

The process described herein may take on various forms or embodiments, some of which are preferred over others and which are described hereinbelow.

The feed to the steam cracking operation can contain any suitable hydrocarbon, i.e. one that will crack to yield desirable unsaturated products. Generally, however, the steam cracking process is most applicable to the cracking of feeds consisting essentially of cyclic or acyclic hydrocarbons, preferably saturated hydrocarbons. Thus, hydrocarbon materials which can be utilized as feed stocks include such cyclic hydrocarbons as cyclopropane, cyclobutane, cyclopentane, cyclohexane, cyclooctane, cyclo-dodecane, etc., and mixtures thereof. Acyclic hydrocarbon feed can include any alkane, namely aliphatic hydrocarbons of the methane series or mixtures of such alkanes with cycloalkanes. Preferred feeds are those saturated hydrocarbons containing about 2 to about 24 carbon atoms, most preferably C₂-C₁₂ alkanes and mixtures of such alkanes, e.g. ethane, propane, butane, isobutane, hexanes, octanes, etc., n-hexadecane, eicosane and naphthas boiling in the range of 90°-430° F., gas oils of 450°-800° F. boiling range, and kerosenes of 430°-55° F. boiling range can also be effectively cracked in the process. The feed is generally diluted with steam to increase cracking efficiency and the feed mixture is usually comprised of about 20-80 mol percent steam, preferably 20-60 mol percent, more preferably 30-60 mol percent steam.

It should be noted that the type of feed conventionally fed to a steam cracking furnace is limited by the tendency to deposit coke on the tube walls while it is being cracked to the conversion level required to meet a certain product demand. Thus, highly unsaturated and cyclic feedstocks tend to be heavier cokers, and are more refractory to undergo desirable cracking reactions than paraffins and naphthenes of comparable molecular weight. Similarly, higher boiling feedstocks will deposit more coke than lighter feedstocks when subjected to the same cracking severity. Since the present invention permits the most severe portion of the cracking reaction (both from a conversion level and a temperature level point of view) to be carried out in a zone where coking on the walls is not detrimental to heat transfer, etc., feedstocks previously considered undesirable can now be fed to a steam

cracker. These stocks, such as olefins, highly aromatic fractions and heavy feeds (boiling above 800° F.) can be cracked to low severity (10-40%) in the steam cracker, but to any desired conversion level in the subsequent post-reactor.

As previously mentioned the feed, hydrocarbon and steam, is heated in a convection zone to about 1000-1100° F. but below cracking temperatures. The heated feed is then passed to a radiant zone where the steam cracking reaction occurs. Here, the tubes are heated to about 1800° F.-2000° F. The residence time in the cracking zone ranges from about 0.1 to 10 seconds, preferably 0.1 to 1.0 second, the higher the temperature the lower the residence time to obtain a given conversion level. Pressures within the tubes are not critical and can range from about 0-50 p.s.i.g., but higher pressures, e.g. up to about 150 p.s.i.g. can be tolerated. In order to maximize the yield of unsaturates, low hydrocarbon partial pressures are desirable. Steam acts as an effective diluent for this purpose.

Now, in order to increase the overall conversion of cracked feed and particularly the ethylene yield, a hot gaseous stream resulting from electrically heating a suitable material or materials is injected into the steam cracking product mixture either within the radiant section or as the effluent emerges from the radiant section. Preferably, however, the gaseous stream produced by electrical heating is injected into the steam cracker effluent, i.e. outside the radiant zone. In this manner, the heat of cracking can be supplied in the furnace at a more favorable temperature level and maximum cracking in the furnace is obtained compared to injecting hot material at an intermediate point in the radiant coil. Generally, the gaseous stream from electrical heating is at a temperature ranging from about 2000-4000° F., preferably 2300-4000° F., more preferably 2600-4000° F. The hot electrically heated stream is mixed in sufficient quantity with the steam cracked product to raise the temperature of the mixed effluent streams to below about 2500° F., preferably 1700-2200° F., more preferably about 1750-2000° F. when the arc effluent contains acetylene. At these temperatures unconverted (or uncracked) hydrocarbon feed emerging from the radiant section is cracked and overall conversion of hydrocarbon feed is increased. As mentioned, the temperature of the mixed stream should not exceed about 2500° F., since above such temperatures the water-gas reaction leading to CO formation begins to become excessive. The temperature boost supplied by the electrically heated stream is generally maintained for a period of about 1-10 milliseconds before quenching to stop all further reaction.

The electrically heated hot gaseous stream utilized to boost the temperature of the hydrocarbon cracking feed can be obtained by using any suitable electric heating means, i.e., resistance elements, an electric arc or plasma-jet. Preferably, the electric arc is produced by what is generally known as a transpiration electrode. Briefly, a transpiration electrode consists of a porous anode through which the reactant is allowed to flow into the arc (see U.S. Pat. 3,209,193). Other arc heating devices which have been developed are described in the literature and can be advantageously employed in the present invention. They include the Knapsack-Griesheim arc (see U.S. Pat. 2,916,534), the Union Carbide arc (U.S. Pat. 3,051,639) where methane is cracked by means of electrically superheated hydrogen; also the Du Pont arc (Chemical Week, Jan. 18, 1964, pp. 64-65) and the Huels arc (Chemical Week, May 18, 1957, pp. 112-116), both of which have been operated commercially over extended periods of time.

The stream which is electrically heated can comprise a variety of different materials so long as the effluent from the arc chamber does not contain CO or CO₂ in quantities sufficient to contaminate the steam cracking product. For example, steam, or inert gases, e.g. nitrogen,

argon, etc. can be electrically heated and utilized to boost the temperature of the steam cracked product. However, these are not preferred materials due to the extra condensation and compression loads, respectively, placed on downstream separation facilities, and the contamination of the hydrogen product with argon or nitrogen, etc. A preferred material that can be electrically heated is hydrogen. Still more preferred materials are hydrocarbons which when subject to electric arc temperatures, e.g. above about 2200-2500° F., crack to mixtures rich in acetylene and hydrogen. The use of such materials is highly advantageous since acetylene is a valuable material which is also produced in steam cracking operations. However, the relatively low yield of acetylene from steam cracking, e.g. 0.5-1.0%, makes it impractical to recover it and acetylene is usually hydrogenated. By this process, however, added to the acetylene in the steam cracked product is the acetylene content of the electrically heated (cracked) hydrocarbons and when the temperature of the steam cracked product is raised after injection of the hot stream from electrical heating, additional acetylene is produced, e.g. 3-5% and, therefore, the acetylene is now present in sufficient quantity for separation and recovery. It should be noted that while acetylene recovery from the large quantity of cracked gases is an expensive process, its cost is compensated for somewhat by the fact that thorough removal and recovery of acetylene from the cracked gas obviates the need for the conventional acetylene hydrogenation facilities.

The hydrocarbon utilized in the electric arc cracking can be any hydrocarbon, e.g. aliphatic, cyclic, aromatic, etc., ranging from C_1 to about C_{20} , preferably, C_1 to C_{10} . Most preferably, the hydrocarbon is methane or a stream which is primarily methane, i.e. natural gas, liquefied petroleum gas, methane-hydrogen streams, and the like. Nevertheless, it is most preferable to utilize any excess hydrocarbon produced in steam cracking by separating and recycling that product to the electric arc. Thus, such products as unconverted feed, steam cracked naphthas, C_4 - C_5 olefins and diolefins, and the like, which are in excess supply at any given time, i.e., of low value at that time, can be utilized as feed to the electric arc. It is noted that methane is also a product of steam cracking and, therefore, in the most preferred case, methane is separated and utilized as feed to the electric arc.

Since the high temperatures utilized in electric arc cracking of hydrocarbons are conducive to carbon formation, it is generally desirable to employ hydrogen in the feed to the arc to inhibit carbon formation. Generally, the tendency towards carbon formation increases as the molecular weight of the feed to the electric arc increases. Usually, at least about 20% molecular hydrogen in the feed to the arc is sufficient to inhibit carbon formation, and preferably about 50 to 200% hydrogen is present in all hydrocarbon feeds to the electric arc so as to direct the cracking to acetylene rather than coke. In the case of the transpiration electrode, hydrogen content of the feed stream as low as 1-5 mol. percent can be tolerated with feeds which are normally gaseous (C_1 - C_3) and which do not reach their thermal cracking temperature (1000-1400° F.) until they have passed the porous anode (vide supra). However, even with the transpiration arc, it may be advantageous to have a 20-75% concentration of hydrogen in the arc feed.

When an acetylene rich arc effluent is produced it is necessary to quench the effluent rather quickly, e.g. about 1 millisecond, or at a rate of 10⁶° F./sec. (see Kampfner and Krause, HTP: After Five Years, Hydrocarbon Processing, vol. 45, No. 4, April 1966, p. 187) to below about 2000° F., preferably below about 1800° F., to stop further reaction and preserve the acetylene yield.

Having now described the inventive process, it will be further illustrated by reference to the following examples. However, no limitations are to be implied from these

examples since variations and modifications thereof will be obvious to those skilled in the art.

EXAMPLE 1

- 5 A naphtha feedstock boiling in the C_5 /350° F. range is cracked in a tubular furnace in the presence of steam. With a total residence time of 0.3 second and a 1550° F. coil outlet temperature, conversion of the feed to C_3 and higher material is 63.7 wt. percent. The yield of ethylene is 30.4 wt. percent, of acetylene 0.6 wt. percent. The effluent from this cracker is then subjected to additional cracking by admixture with a hot, inert gas (argon), so that the temperature of the mixture is 1900-2000° F. for 1-1.5 $\times 10^{-3}$ seconds before quenching to below 500° F. 10 The conversion of the feed mixture to C_3 and lighter material is increased to 75.6 wt. percent and the yields of ethylene and acetylene are raised to 38.5 and 3.5 wt. percent respectively.

EXAMPLE 2

- 20 A virgin gas oil feed stock boiling above 430° F. is cracked in a tubular furnace in the presence of steam. Coil outlet temperature of 1500° F. results in a C_3 and lighter material production of 46.0 wt. percent on feed, including methane 9.0, ethylene 17.0 and acetylene 0.3 wt. percent on feed. At the same time, a mixture consisting of 95 mol percent methane, 5 mol percent hydrogen is passed through a high temperature electric arc which results in the formation of a 3000° F. gas product comprising 72.8 mol percent hydrogen, 2.6 mol percent methane, 3.9 mol percent ethylene and 18.3 mol percent acetylene. The effluents from the tubular cracker and the electric arc chamber are rapidly mixed. The mixture reaches a temperature of 1750° F.-1800° F. and is held for 2-3 $\times 10^{-3}$ seconds before quenching to a temperature below 800° F. The yield of light material derivable from the gas oil feed stock is increased to the following values: Total C_3 and lighter 65.1 wt. percent; methane 15.4, ethylene 29.9, acetylene 2.1 wt. percent.

EXAMPLE 3

- 25 A gas oil is cracked in a tubular furnace in accordance with Example 2 and the effluent mixed with electric arc effluent to obtain a high severity, cracking temperature of 1750-1850° F. The effluent from this cracking zone is quenched and separated into its components. Hydrogen is taken off as a 95% purity product, and 96% of the methane produced is recycled to the electric arc cracking zone in admixture with a small amount of hydrogen. Overall yields of product from 1000 lbs. of feed include: 30 H_2 1960 SCF; acetylene 107 lbs.; ethylene 350 lbs.

What is claimed is:

1. In a process for thermally cracking a hydrocarbon feedstock which comprises passing a reaction mixture containing said feedstock and steam to a multiplicity of tubes arranged in a cracking furnace, subjecting the tubes to radiant heat sufficient to raise the temperature of the reactants in the tubes above the cracking temperature of the hydrocarbons, cracking the feed hydrocarbon, and recovering an effluent containing steam, cracked hydrocarbons, and unconverted feed hydrocarbon, the improvement which comprises injecting into the reaction mixture, after the cracking of the feed hydrocarbons has been initiated, an electrically heated gaseous stream which comprises a material selected from the group consisting of hydrogen, inert gases, steam, cracked hydrocarbons, and mixtures thereof, the gaseous stream being at a temperature ranging from about 2000°-4000° F. in order to effect cracking of the unconverted feed hydrocarbon.
2. The process of claim 1 wherein the gaseous stream is injected into the reaction mixture while the reaction mixture is in the radiant section of the cracking furnace.
3. The process of claim 1 wherein the gaseous stream is injected into the reaction mixture after the reaction mixture leaves the cracking furnace.

4. The process of claim 3 wherein the gaseous stream injected into the reaction mixture comprises inert gases.

5. The process of claim 3 wherein the gaseous stream injected into the reaction mixture comprises hydrogen.

6. The process of claim 3 wherein the gaseous stream injected into the reaction mixture comprises steam.

7. The process of claim 3 wherein the gaseous stream injected into the reaction mixture comprises cracked hydrocarbons.

8. The process of claim 7 wherein the cracked hydrocarbons are predominantly acetylene.

9. The process of claim 8 wherein the gaseous stream also contains hydrogen.

10. In a process for thermally cracking a hydrocarbon feedstock which comprises passing a reaction mixture containing said hydrocarbon feedstock and steam through a multiplicity of tubes arranged in a cracking furnace, subjecting the tubes to radiant heat sufficient to raise the temperature of the tubes to a range of from about 1800° F. to about 2000° F., cracking the feed hydrocarbon in said tubes for a period of time in the range of from about 0.1 to about 1.0 second, and recovering an effluent containing steam, cracked hydrocarbons, and unconverted feed hydrocarbon, the improvement which comprises separating a portion of the cracked hydrocarbons, passing the separated hydrocarbons to an electrical heating means, heating the separated hydrocarbons to a temperature ranging from about 2000°-4000° F., thereby cracking the separated hydrocarbons, and injecting the electrically heated, cracked hydrocarbons into the effluent from the cracking furnace thereby causing additional cracking of the unconverted feed hydrocarbon.

11. The process of claim 10 wherein the electrically heated, cracked hydrocarbons contain, in greatest concentration, acetylene.

12. The process of claim 10 wherein the separated hydrocarbons are mixed with hydrogen prior to electrical heating.

13. The process of claim 10 wherein the separated hydrocarbons are electrically heated to temperatures ranging from about 2300°-4000° F.

14. The process of claim 10 wherein the effluent from the steam cracker is at a temperature ranging from about 1200° F.-1800° F.

15. The process of claim 10 wherein the portion of hydrocarbons separated from the effluent of the cracking furnace is primarily methane.
